UNITED STATES PATENT OFFICE.

GEORGE WELLINGTON HEENE, OF CLEVELAND, OHIO.

WORKMAN'S TIME-RECORDER.

SPECIFICATION forming part of Letters Patent No. 461,478, dated October 20, 1891.

Application filed February 18, 1891. Serial No. 381,380. (No model.)

To all whom it may concern:

Be it known that I, GEORGE WELLINGTON HEENE, a citizen of the United States, residing at Cleveland, in the county of Cuyahoga and State of Ohio, have invented certain new and useful Improvements in Workmen's Time-Registers, of which the following is a specification.

This invention relates to a device for self-registering the time of entering and the time of departure of workmen into and from a factory or workshop.

The invention consists in the novel constructions and combinations of a mechanism for performing the operations above stated, substantially as hereinafter described, and pointed out in the claims.

In the accompanying drawings, Figure 1 is a perspective view of my new registering device. Fig. 2 is a vertical cross-section showing the lever-operating mechanism. Fig. 3 is a horizontal section on line 3 3 of Fig. 2, with portions omitted and others broken away for showing chart-cylinder. Fig. 4 is a sectional view of one of the registering-punches and lever which actuates it.

A represents a cabinet of suitable form and dimensions for containing the registering mechanism.

B B are metal bars having face-plates, which are securely fitted in the side walls of the cabinet, the face-plates bearing against the outer surfaces of the cabinet-walls. They may be placed in rows and upon opposite sides of the cabinet, as may be most convenient. These bars are bored at suitable intervals for the insertion of pull-rods C C, the outer ends of which are provided with curved handles or knobs c c for the convenience of grasping for pulling. The boxes are somewhat larger than the rods, and there is provided a retracting-spring S on each rod within the boxes, bearing against the front end of the boxes and against a pin c², fixed in the rods, which pins also slide in slots in the upper sides of the boxes. These pins permit the rods to have longitudinal movement, but prevent turning. The rods are also provided with branch pins or hooks b, which enter holes through the face-plates below the rods. Upon said pins or hooks are hung checks or tags T, removable only when the rods are pulled out, said

pins being a little shorter than the movement of the rods to allow for the removal and replacement of the checks, but not before the 55 register mechanism has operated to record such removal or replacement.

E E are brackets fixed in the corners of the cabinet for supporting the central punching mechanism. D is a middle bar supported by 60 said brackets, and is perpendicularly perforated for containing punch-pins F. G G are side wings on the bar D, having slots, in which are pivoted angle-levers d d, employed for actuating the said punch-pins. The upper 65 ends of the angle-levers are connected to the pull-rods C C by connecting-rods H H. To the other ends of the angle-levers are pivotally attached pawls p, which serve to lift the punch-pins when the levers are pulled, but 70 which are allowed to pass back under the heads f of said pins when the levers move back again. Upon the punch-pins are placed, between their heads and the top of supporting-bar D, springs g g, which serve to forcibly 75 throw the pins down when released from the said pawls.

Beneath the punch-pins is located a cylinder or roller K, to which rotary motion is imparted by means of a clock L, set in the wall 80 of the cabinet and suitably connected by gear which revolves the cylinder at the same rate of speed that the clock measures off the time.

On the cylinder is placed a chart numbered across the top in accordance with punch-pins 85 and divided off into hour and minute spaces from top to bottom. These charts are removed daily and present an accurate record of the arrival and departure of the workmen.

From the foregoing it will be seen that the 90 operation of this device is as follows: The workman on arrival removes the numbered check to which he is entitled by pulling the rod having that number, thus registering such number in that numbered column on the 95 chart and indicating the exact time of his arrival, and when he departs he replaces his check by a repeated movement of the registering mechanism.

Having described my invention I claim— 100

1. In a recording mechanism, the combination, with cabinet A, bars B, provided with boxes and holes, pull-rods C, having hooks b for holding check-tags T and provided with

retracting-spring S, constructed to operate substantially as and for the purpose specified.

2. In a recording mechanism, the combination, with pull-rods C, having hooks b and supported in the bars B, substantially as described, of the recording mechanism, consisting of the perforated bar D, supported by brackets E and provided with punch-pins F, the side slotted wings G, angle-levers d, pivotally mounted in said wing and having pawls p, and the connecting-rods H, connecting the angle-levers d with the pull-rods C, constructed and arranged substantially in the manner and for the purpose set forth.

15 3. In combination with the punch-pins F,

the springs g g², the angle-levers d, and their pawls p, substantially as and for the purpose specified.

4. The combination of check-holding pull-rods C, mounted in the bars B, fixed in the 20 sides of cabinet A, bracket E, supporting registering mechanism substantially as that described, a chart-holding roller K, and clock L, constructed and arranged to operate substantially in the manner and for the purpose 25 set forth.

GEORGE WELLINGTON HEENE.
